(57) **CLAIM**

The ornamental design for chaps, as shown and described.

DESCRIPTION

FIG. 1 is a front perspective view of a pair of chaps, showing my new design, the broken lines partially showing a human form and shoes being to illustrate the use of the design, and forming no part of the claim;

FIG. 2 is a back perspective view thereof;

FIG. 3 is a left side view thereof;

FIG. 4 is a right side view thereof; and,

FIG. 5 is a top view thereof.

1 Claim, 2 Drawing SheetsFIG. 1

FIG. 2
